UNITED STATES PATENT OFFICE.

ERNEST HENRY JONES AND GEORGE WATERS TARVER, OF LONDON,
ENGLAND.

HANDLE-BAR FOR BICYCLES.

SPECIFICATION forming part of Letters Patent No. 624,657, dated May 9, 1899.

Application filed March 9, 1897. Serial No. 626,588. (No model.)

To all whom it may concern:

Be it known that we, ERNEST HENRY JONES and GEORGE WATERS TARVER, subjects of the Queen of England, residing at London, 5 England, have invented certain new and useful Improvements in or Relating to Handle-Bars for Cycles and other Vehicles, (for which we have obtained Letters Patent in England, No. 19,624, dated September 4, 1896,) of which 10 the following is a specification.

This invention relates to handle-bars for cycles and other vehicles, its object being to render them readily adjustable while the machine is being ridden to bring the handles 15 to a position convenient to the user and retain them securely therein under the stresses which come upon them in service.

According to this invention the handle-bar is made in two parts, one for each handle, 20 each part being hinged at the inner end—that is to say, the end opposite to its handle—to a head suited for retention in or at the upper end of the steering-tube of either new or 25 existing cycles or the equivalent part of other vehicles. These inner ends of the halves of the handle-bar are geared together by an adjusting device in operative connection with both the halves of the handle-bar and provided either in the head or on the steering- 30 tube, so that by its operation both the handles may be turned up or down about their pivots or hinges through equal angles to the extent desired. It is understood that the 35 gearing is in all cases so arranged that both halves of the bar move simultaneously up or simultaneously down.

Figure 1 is a vertical central section, partly in elevation, of a head such as is hereinbefore referred to and the inner or hinge ends of the 40 two halves of the handle-bar, together with worm adjusting-gear carried by the head. Fig. 2 is a transverse section on the line 2 2 of Fig. 1.

Like letters indicate like parts throughout 45 the drawings.

In the above-described figures of drawings, A is the head, which is tubular and T-shaped, the stem A' of the T being made of any form

which will enable it to be engaged firmly with the upper end of the steering-tube.

B B' are taper-pins, which are screwed into the opposite ends of the transverse portion A² of the head and form pivots which the two portions C C' of the divided handle-bar encircle and turn about. The parts C² C³ of 55 the halves C C', respectively, are spherical and of such diameter as to fit the interior of the transverse tubular portion A² of the head A. Each of these spherical portions is provided with a rack C⁴.

D is a vertical worm, to which is fixed a large milled head D'. It turns in bearings in the axial line of the head A, so as to gear with the rack C⁴ on each of the spherical parts C² C³, and is retained in place by a plug A³, 60 through which its lower end D² passes and in which that end is retained by a nut D³ or other means capable of preventing endwise movement. If desired, packing-rings, such as E, can be inserted between the upper side 65 of the plug A³ and the shoulder D⁴ on the spindle of the worm D to adjust it endwise, as may be desired.

The worm D is preferably tapered, as shown, from one end to the other, the milled head 70 being fixed upon the larger upper end. By having it tapered it will take up, if lowered endwise, any wear between it and the racks C⁴, so as to prevent backlash and rattling.

It will be seen that by turning the tapered 80 worm by means of the milled head D' the portions C C' of the handle-bar may be adjusted simultaneously to the desired angle.

It is not essential that spherical parts C² C³ should be employed at the hinge ends of the 85 halves C C' of the handle-bar, for any other convenient shape preferably fitting a correspondingly-shaped tube or socket of the head can be adopted.

We claim—

A handle-bar for cycles comprising two parts or sections, a stem to which one end of each of said parts is pivotally connected, said pivotal ends being provided with oppositely-located rack or toothed portions, a tapered 95 worm adapted for endwise or longitudinal

movement arranged between and engaging with said toothed portions and adapted to operate the handle-bar sections simultaneously, and means for adjusting the worm 5 endwise and holding the same in adjusted position, as and for the purpose set forth.

In witness whereof we have hereto set our

hands in the presence of the two subscribing witnesses.

ERNEST HENRY JONES.

GEORGE WATERS TARVER.
